CLAIM

The ornamental design for a cake caddy, as shown and described.

DESCRIPTION

FIG. 1 is a top front side perspective view of a cake caddy showing my new design;

FIG. 2 is a top view of the cake caddy;

FIG. 3 is a front view of the cake caddy;

FIG. 4 is a rear view of the cake caddy;

FIG. 5 is a bottom view of the cake caddy;

FIG. 6 is a left side view of the cake caddy; and,

FIG. 7 is a right side view of the cake caddy.

The broken lines show portions of the cake caddy and form no part of the claimed design.
